UNITED STATES PATENT OFFICE.

JOHN H. HOUT AND WILLIAM H. GROTHUS, OF COLUMBUS, OHIO.

GUARD ATTACHMENT FOR MOLDING-MACHINES.

SPECIFICATION forming part of Letters Patent No. 671,212, dated April 2, 1901.

Application filed April 9, 1900. Serial No. 12,045. (No model.)

To all whom it may concern:

Be it known that we, JOHN H. HOUT and WILLIAM H. GROTHUS, citizens of the United States, residing at Columbus, in the county 5 of Franklin and State of Ohio, have invented a certain new and useful Improvement in Guard Attachments for Molding-Machines, of which the following is a specification.

Our invention relates to safety attachments 10 for the bit-carrying spindles of woodworking machinery, such as molding-machines or shapers; and the objects of our invention are to provide a feed-guard or safety attachment whereby the danger of the fingers of the operator of the machine being cut is reduced to a minimum, to construct said attachment in an inexpensive and simple form, and to produce other improvements, the details of which will be more fully pointed out hereinafter. 15

These objects we accomplish in the manner illustrated in the accompanying drawings, in which—

Figure 1 is a view in elevation of a knife or bit carrying spindle having our improvement thereon and showing a portion of the machine-table in section. Fig. 2 is a plan view of our safety attachment, and Fig. 3 is a vertical section of the safety attachment and the adjoining rings or collars.

Similar numerals refer to similar parts throughout the several views.

1 represents one of the usual bit or knife carrying spindles, the latter being provided with the usual or desirable form of upper and lower knife-retaining collars or heads 2 and 3, between which are supported in the usual manner the inner portions of suitable bits or cutting-tools 4. At a point on the spindle below the knives or bits and immediately beneath the table or top plate 5 of the machine we provide a ring or collar 6, which, although neatly fitting about said spindle, is sufficiently loose thereon to admit of its being rotated independently of the latter. Fitting in a corresponding manner about this ring 6 is a collar 7, the body of the latter preferably being of less thickness or height than the ring 6, which it surrounds and with which it is held in engagement by friction. The outer edge 40 of the collar 7 is provided on one side with an outwardly-projecting cam-body 8, the outer surface of the latter, which is of greater height

than the body of the ring 7, extending on a curved tangential line from the periphery of said ring 7, thus greatly increasing its width 55 toward its outer termination. The outer surface of the tangential cam-body, formed as above described, is preferably roughened or toothed, as indicated at 9, for the purpose hereinafter set forth, while the upper and 60 lower surfaces thereof may be recessed, as indicated at 10, to impart desirable lightness thereto. From the lower side of the cam projection 8 we cause to extend a stop-pin 11. Below the ring or collar 6 we preferably provide the spindle, above the head of the boxing 12, with the usual collar 13, and below the latter, on said boxing-head, we provide a fixed ring 14, having an upward stop projection 15 on its periphery, the latter being in the path 70 of the stop-pin 11 when the collar 7 is rotated.

In utilizing the above-described invention for the purpose of reducing the danger of having the fingers of the operator injured by the knives the strip or body of wood to be cut by 75 said knives is instead of being started, as usual, against a collar of equal thickness on the spindle placed in contact with the serrated surface of the wider portion of the cam projection 8, said strip being gradually forced 80 inward and the collar 7 rotated until the strip to be cut, following the inward curve of the surface of the cam 8, is against the body of the ring 7 and subject to the cutting action of the knives or bits.

In case, as often happens with machines of this class, the knives stick or catch in the wood which is being operated on the wood will be thrown outward by the movement of the cam toward the operator, so that the 90 hands of the operator, which are grasping the wood, will be brought out of the path of the knives. This outward movement of the wood is accomplished partly through the engagement thereof with the serrated surface 95 of the cam projection and partly through frictional engagement of the inner ring 6 and ring 7 and a corresponding engagement of said ring 6 with the spindle, the latter being rotated toward the operator. Although the 100 ring 6 is rotatably mounted upon the spindle, a sufficiently close fit is attained between these parts to insure the movement of the rings 6 and 7 with the spindle when the ring

7 is released from pressure of the work. It will thus be seen that the device herein described serves to secure the safety of the operator's hands in handling the strip to be cut during the feeding of said strip into engagement with the knives, and, further, serves to throw the work and hands of the operator out away from the knives in case of a stoppage of the cutting action or splitting of the wood.

10 It will be seen that the outward-swinging or return movement of the ring 7 will be limited by the engagement of the pin 11 with the ring projection 15, said pin being normally in engagement with said ring projection.

15 Although we have described the ring 13 in connection with the device herein shown, it is obvious that any desired number of collars or rings might be employed above or below 20 the safety-collar as the character of the machine or occasion might require. It is also evident that while the employment of the inner ring 6 is considered desirable said ring 6 may be omitted and the ring 7 made to fit

loosely about the periphery of the spindle. 25 It will be observed that our improved safety device is simple in construction and that the same may be produced at a low cost of manufacture and readily connected with any of the ordinary forms of bit-carrying spindles. 30

Having now fully described our invention, what we claim, and desire to secure by Letters Patent, is—

In a safety attachment for bit or knife carrying spindles, the combination with the spindle and bits, of a collar rotatably mounted on said spindle, and having a sufficient frictional engagement therewith to insure its rotation with the spindle when the collar is released from external pressure said collar having a 35 cam projection extending tangentially therefrom, substantially as specified.

JOHN H. HOUT.
WILLIAM H. GROTHUS.
